FOOTBALL BENCH SHELTER

Edward H. Cooper, 2 E. Benedict Ave., Havertown, Pa.

Filed Mar. 22, 1963, Ser. No. 74,082

Term of patent 3½ years

(Cl. D13—1)

Fig. 1

FIG. 1 is a perspective view of a football bench shelter showing my new design, the bench is disclosed in broken lines for illustrative purposes only.

FIG. 2 is an end view of my invention, the other end being exactly similar and opposite.

FIG. 3 is a top plan view of my invention.

FIG. 4 is a front elevation view of my invention.

FIG. 5 is a rear elevation view of my invention.

I claim:

The ornamental design for a football bench shelter, as shown and described.
